UNITED STATES PATENT OFFICE

GERSON KAUFMAN, OF NEW YORK, N. Y.

DESIGN FOR A SYRINGE NOZZLE

Application filed August 25, 1930. Serial No. 36,761. Term of patent 14 years.

To all whom it may concern:

Be it known that I, GERSON KAUFMAN, a citizen of the United States, residing in the city, county, and State of New York, have invented a new, original, and ornamental Design for a Syringe Nozzle, of which the following is a specification, reference being had to the accompanying drawing, forming part thereof.

Figure 1 is a view of a syringe nozzle showing my new design; and

Figure 2 is an end view of the same.

I claim:—

The ornamental design for a syringe nozzle substantially as shown.

GERSON KAUFMAN.
